United States Patent Office.

THOMAS J. McGARRY, OF CLEVELAND, OHIO.

Letters Patent No. 64,123, dated April 23, 1867.

IMPROVEMENT IN VESSELS FOR STORING AND TRANSPORTING OIL.

The Schedule referred to in these Letters Patent and making part of the same.

TO ALL WHOM IT MAY CONCERN:

Be it known that I, T. J. McGARRY, of Cleveland, in the county of Cuyahoga, and State of Ohio have invented certain new and useful Improvements in Oil-Tanks; and I do hereby declare that the following is a full and complete description of the construction of the same, reference being had to the accompanying drawings, making a part of this specification, in which—

Figure 1 is a side view of the tank.

Figure 2 is an end view of the same.

Figure 3 is a detached longitudinal vertical section.

Like letters of reference refer to like parts in the views.

This tank consists of the elliptical or barrel-shaped vessel A, fig. 1, which is constructed of iron, and of a capacity greater or less, as may be required. Within the outer shell of this tank is an inner one, or lining, B, fig. 3, and between which is formed the annular chamber C; so also are the ends chambered by a double head, D, fig. 3, is a man-hole, and is provided with a plate, a, around the under side of which is a deep flange, which is made to fit into a corresponding groove surrounding the man-hole. This plate is made tight, and kept in place by the screw E. At the under side of the tank is an outlet, F, leading from the interior of the tank, and which is closed by a valve, G, fig. 3. This valve is operated by the rod H, which is seen to project through the upper side of the tank, and terminates with a handle, I. J is also an outlet leading from the chamber C. At the upper side is an inlet, K, leading to the interior of the tank. L is an inlet leading to the chamber C. These inlets and outlets are closed by screw-caps, and by the means of which they are kept tight and secure. Each end of this tank is provided with a journal, b, by which it is suspended upon a pair of trusses, M, and made to revolve for a purpose hereafter shown. To aid in the support of the tank a pair of additional saddles, N, are provided, and upon which the ends of the tank are supported, as shown in fig. 1. O is supposed to be the platform of the railroad truck, and upon which the tank is mounted, as above described. Under the feet of the trusses N is placed a spring, e, for the purpose of an easier carriage of the filled tank, the transportation of which may be by land or water.

This tank is filled with oil through the inlet K, and then closed by the screw-cap and man-hole plate, above described. The annular chamber is then filled with water through the inlet L, and then closed in the same manner. By this arrangement the oil is entirely surrounded by water, and is therefore completely protected; hence the danger of taking fire while in transportation or otherwise is wholly avoided, as no part of the outside shell of the tank is in contact with the oil; also the water prevents any leakage of the oil to the outside. In order to draw the oil from the tank a tube or conductor is attached to the outlet F. For the greater convenience of attaching the conductor, or for other needful purposes, the tank may be turned upon the journals referred to. The oil is then drawn off by raising the valve G by means of a thread cut upon the rod H, and in the stuffing-box, through which the rod is projected, as above said.

As before remarked, this tank is shown as being mounted upon a platform of a railroad truck. In this position it is easily and conveniently transported, and without danger of displacement. In order to transport the tank by steamboat, vessel, or other such conveyance, it is taken from the trusses and stowed away in the hold in the same manner as ordinary barrels, which it will be seen will occupy no more room than a cask of equal capacity, and is far safer and more durable.

What I claim as my improvement, and desire to secure by Letters Patent, is—

1. The tank A with shell and lining B, having a water-chamber at the sides and ends, in combination with inlets and outlets, arranged as and for the purpose substantially as set forth.
2. Hanging the tank upon journals or bearings, as and for the purpose set forth.
3. The saddles N, provided with spring bearings, in combination with the tank, substantially as and for the purpose set forth.

THOMAS J. McGARRY.
